UNITED STATES PATENT OFFICE.

JOHN H. RITTER, OF SEATTLE, WASHINGTON.

BULLET-PROTECTING SCREEN.

1,180,431.

Specification of Letters Patent. Patented Apr. 25, 1916.

Application filed August 15, 1914. Serial No. 856,912.

To all whom it may concern:

Be it known that I, JOHN H. RITTER, citizen of the United States, residing at Seattle, in the county of King and State of Washington, have invented a certain new and useful Improvement in Bullet-Protecting Screens, of which the following is a specification.

My invention relates to improvements in bullet proof screens and the object of my improvement is to provide a screen or grating that may be used as a partition or guard-fence to protect cashiers in places that are subject to attack by robbers, as in banks, railroad ticket offices, and the like places where large amounts of money are handled and stored.

A further object of my improvement is to provide in combination with such bullet proof guard-fence a section of bullet proof screen that is adapted to be raised automatically to close an opening as a cashier's window, when an attack by a robber from the outside is threatened, and a still further object of my improvement is to provide a screen that will act as a shield against bullets fired from the outside but which will permit bullets to pass through it when fired from the inside thereof to inflict damage to a person on the other side.

I accomplish these objects by structures illustrated in the accompanying drawings in which—

Figure 1 is a view in perspective of a section of a bank counter to which my invention has been applied; Fig. 2 is a view in vertical section on broken line A, A of Fig. 1; Fig. 3 is a view in horizontal section on broken line B, B of Fig. 2 showing a vertically movable gate in a raised position; Figs. 4 and 5 are enlarged fragmentary views in cross-section of details of my invention, and Fig. 6 is a view in cross-section illustrating a modified form of my invention.

Referring to the drawings, throughout which like reference numerals indicate like parts, 7 is a cashier's counter in a bank or office where money or other valuables are handled, and 8 is a screen-like gate for the window behind which the cashier stands to transact business with persons that approach such window from the outside.

A guard-fence or screen is constructed of a plurality of flat metal bars 9, that are placed with their adjacent sides parallel

with each other and secured at fixed distances from each other by shafts or bolts 10 and spacing washers 11, as more clearly shown in Fig. 4, such bars 9 being disposed, when secured together, to present their edges inwardly and outwardly and being sufficiently close one to another that a bullet upon striking the edges of the bars 9, on the outside of such screen will be entirely stopped or will be checked to such an extent that if any portion of it passes through such screen between adjacent bars then the force of such portion will be so nearly spent that it can inflict no serious injury to a person standing behind such screen. The screen formed of the bars 9 extends upwardly from the front edge of the counter 7 while the opening through which business is to be transacted is provided with a normally closed grate-like gate of a well known form embodying vertical bars 8 and on each side of such opening I have constructed a guard fence 12 disposed to extend rearwardly from, and at right angles to, the plane of said screen and like said screen such guard-fence is made of bars like the bars 9; such two guard-fences serving to prevent one from the outside from reaching to gain access to money or other valuables placed on the counter 7 on either side of the space through which business is transacted.

For the purpose of preventing bullets from passing through the grating formed by the bars 8 I have provided a vertically movable screen-gate 13 that is constructed of bars like bars 9 and which is adapted to be automatically raised by a weight 14 when such screen-gate 13 is released, the weight 14 being connected with the screen-gate 13 by a cable 15 that passes over a pulley 16 and such screen-gate 13 being adapted to be locked in its lowered position by a hook 17 that is provided on the end of a fulcrumed foot trip lever 18 which trip lever is adapted to be acted on by a compression spring 19 to keep the hook 17 in engagement with the screen-gate 13 and such trip lever 18 is provided on its inner end with an arm 20 that may engage the under surface of the lower edge of the screen-gate 13 and is thus adapted to give such screen-gate 13 an upward thrust when the outer end of the foot trip lever 18 is pressed downwardly to release the screen-gate 13 to cause it to move quickly in an emergency.

The screen-gate 13 preferably is pro-

vided with a channel shaped frame 21 that extends around such grating to strengthen it and on its top edge is a ledge 22 that is adapted to form a part of the counter 7 when said screen-gate 13 is in its lowest normal position.

To prevent the screen-gate 13 from being moved downwardly by a person in front of the counter 7, I have provided a hook 23 that is adapted to engage with the bottom edge of such screen-gate to lock it in its raised position, such hook being formed integral with a fulcrumed lever arm 24 that is pressed by a compression spring 25 which insures the operation of the hook 23 which may be moved to withdraw the hook 23 from engagement with the bottom edge of the screen-gate 13 when a person behind the counter 7 desires to lower such screen-gate 13.

The bars 9 may be disposed in any desired position wherein they will present their edges substantially toward the front, as, for instance, they may be placed in angular positions, as illustrated in the screen-gate 13 shown in cross-section in Figs. 3 and 5, whereby any part of a bullet that breaks or splits off and passes between adjacent bars 9 may be so deflected, as indicated by broken lines in Fig. 3, that it will not hit a person who stands behind such screen-gate 13.

It has been found by experiment that, where the bars 9 are disposed parallel with each other, as shown in Fig. 3, and where the spaces between such bars are substantially narrower than the smallest diameter of bullets in common use, then such bullets when fired against the edges of the bars 9, will be broken or split up that any fragment which does not find its way through the spaces between the bars 9 will have its momentum so reduced that it will not be capable of inflicting serious damage.

In Fig. 6 I have illustrated a modified form of construction of grating wherein I have provided wedge shaped bars 26 that are secured in close proximity to each other in such manner that such bars present their flat surface on one side of the screen-gate and their apices on the other side of such screen whereby bullets that are fired against such grating from one side will strike

against the flat surfaces of the edges of the bars 26 and have their momentum destroyed by such bars 26 while bullets that are fired against such screen from the opposite side will readily force their way between the bars 26 with sufficient force to inflict some damage to objects on the other side; they will strike upon the apices of such bars and with little resistance be split, the separate portions of such bullets passing through the screen with sufficient force to inflict damage.

Obviously a grating constructed in accordance with the principles herein set forth may be used in many places aside from banks and railroad offices and many changes in the details of construction of the gratings and disposition of the bars embodied therein may be resorted to without departing from the spirit of my invention or sacrificing any of its advantages.

What I claim is:—

1. In combination with a frame, a guard screen formed of vertically disposed spaced metal bars rectangular in cross section and secured within the screen, one-half of the bars being inclined in one direction and the remaining half of the bars being inclined in the opposite direction whereby the axial planes of the bars form a series of dihedral angles with their lines of intersection on the outside of said screen.

2. In combination with a frame, a guard screen formed of vertically disposed spaced metal bars rectangular in cross section and secured within the screen, one-half of the bars being inclined in one direction and the remaining half of the bars being inclined in the opposite direction whereby the axial planes of the bars form a series of dihedral angles with their lines of intersection on the outside of said screen, the outer portions of the bars of each half of the screen overlapping the inner portions of the next adjacent bars whereby to cover and protect the entire space behind the screen.

In witness whereof, I, hereunto subscribe my name this 17th day of July, A. D., 1914.

JOHN H. RITTER.

Witnesses:

FRANK WARREN,
A. HASKINS.
